assignors to The Brunswick-Balke-Collender Company, Chicago, Ill., a corporation of Delaware

Application July 20, 1934, Serial No. 52,657

Term of patent 3½ years

To all whom it may concern:

Be it known that we, SAMUEL MARX and GIRAUD
W. BEHREL, both citizens of the United States and both residing at Chicago, in the county of Cook, in the State of Illinois, have jointly invented a new, original, and ornamental Design for a Service Bar Back Counter, of which the following is a specification, reference being had to the accompanying drawing, forming part thereof.

In the drawing—

The figure is a perspective view of a service
bar back counter showing our new design.

We claim:

The ornamental design for a service bar back
counter as shown.

SAMUEL MARX.
GIRAUD W. BEHREL.
